UNITED STATES PATENT OFFICE.

ALBERT H. ULLRICH, OF EVANSTON, ILLINOIS.

DESIGN FOR A HANDLE FOR SPOONS, &c.

SPECIFICATION forming part of Design No. 21,919, dated October 25, 1892.

Application filed May 28, 1892. Serial No. 434,801. Term of patent 7 years.

To all whom it may concern:

Be it known that I, ALBERT H. ULLRICH, a citizen of the United States, residing at Evanston, in the county of Cook and State of Illinois, have invented and produced a new and original Design for Handles of Spoons, &c., of which the following is a specification, reference being had to the accompanying drawings, which are made a part hereof, and in ⁵ which—

Figures 1 and 2 are elevations of opposite sides of a spoon the handle of which embodies the new design.

The handle is wrought to represent the figure of a man wearing the conventional costume of a student—*i. e.*, cap and gown. The skirt of the gown is wound around the lower part of the body and lower limbs, and the outline of the lower limbs is lost in the contour

of the handle. The left arm hangs at the ²⁰ side, and in the left hand is a book. The right arm is folded across the back, and in the right hand is a base-ball.

The leading feature of the design is the representation of a man with one arm hanging at ²⁵ his side and the other folded across his back.

In the drawings I have shown the design applied to the handle of a spoon, but desire to have it understood that it is equally applicable to the handles of other articles. ³⁰

What I claim as new, and desire to procure by Letters Patent, is—

The design for the handles of spoons, &c., substantially as herein shown and described.

ALBERT H. ULLRICH.
